Primary Examiner — Angela J Lee*(74) Attorney, Agent, or Firm* — Alexander Chen(57) **CLAIM**

An ornamental design for an automobile back light, as shown and described.

DESCRIPTION

FIG. 1 is a perspective view of an automotive back light unit. The drawings and descriptions represent the left side embodiment. The design also contemplates a mirror symmetrical embodiment on the opposite side of the vehicle. The dash line included denotes environment and is not part of the claimed design.

FIG. 2 is a front view thereof;

FIG. 3 is a side view thereof; and,

FIG. 4 is a top view thereof.
